UNITED STATES PATENT OFFICE.

HERBERT I. WASHBURN, OF MAGNOLIA, NEW JERSEY.

ELECTRIC SWITCH.

Application filed April 9, 1921. Serial No. 459,847.

To all whom it may concern:

Be it known that I, HERBERT I. WASHBURN, a citizen of the United States, residing in Magnolia, in the county of Camden and State of New Jersey, have invented certain new and useful Improvements in Electric Switches, whereof the following is a specification, reference being had to the accompanying drawings.

10 My invention relates to electric switches, and more especially to electric switches of a rotary type and which may be used either as wall switches for controlling ordinary electric light circuits, or in connection with 15 signaling systems whereby the behavior or movements of any mechanism or apparatus may be definitely ascertained at a remote point. One example illustrative of the application of such switches in the latter of 20 the two uses cited is in association with apparatus for opening and closing the doors of the bulk-heads of vessels, for the purpose of operating visual or oral signals interposed in the controlled circuits to communicate, either to the engineer or pilot, whether 25 or not the apparatus has properly functioned.

The object of my invention is the attainment of utmost simplicity in the construction and operation of switches of the type referred to, so that they may be cheaply manufactured, and prove absolutely reliable in operation to the exclusion of any possibility of becoming deranged in the course of 35 long continued usage.

Other objects and attendant advantages of my invention will become apparent from the detailed description which follows:

In the drawings, Fig. I is a view, partly 40 in plan and partly in section, showing my invention when used as a flush wall switch for controlling electric light circuits and the like.

Fig. II is an elevation of the organization 45 shown in Fig. I, viewed from the bottom of the latter figure, showing, likewise, certain parts in elevation and others in section.

Fig. III is a detail plan section of the 50 switch proper, said section being taken along the line III-III in Fig. II.

Fig. IV is a mid-section through the same.

Fig. V is a plan section viewed in the 55 direction of the arrows V-V in Fig. IV.

Fig. VI is a detail perspective view of

one of the parts of the switch in the form of a block of insulating material which supports certain of the contact elements.

Fig. VII is an end elevation of the switch 60 structure viewed from the right of Fig. IV.

Fig. VIII is a detail plan section along the line VIII-VIII of Fig. IV showing more particularly, the construction of the 65 movable contact carrying member.

Fig. IX is a fragmentary detail section through the movable switch contact carrying member viewed in the direction of the arrows IX-IX in Fig. VIII.

Fig. X is a detail perspective view of the 70 push button of the complete switch organization shown in assemblage in Figs. I and II.

Fig. XI is a perspective view of one of the metallic plungers which cooperate with the movable contact carrying member; and 75

Fig. XII is a view similar to Fig. II of a switch organization embodying my invention in a form useful in connection with signaling apparatus.

Referring more particularly to Figs. I to 80 IX inclusive, 1 designates the dust and moisture proof protective casing of the switch proper. This casing 1 is preferably constructed of cast metal, and has a separate bottom 2, which, after the switch has 85 properly been assembled and the necessary electrical connections made, is permanently secured by soldering, welding, or in any other approved manner. Said casing 1 is filled with a suitable liquid, as shown in 90 Fig. IV, which serves not only to lubricate the movable parts of the switch immersed therein, but also prevents the formation of arcs between the relatively movable contacts of the switch. The liquid may be replenished when necessary through a screw 95 plugged opening 3, see Fig. III.

The top of the casing 1 has an integral upstanding boss 4 which is axially bored to serve as a bearing for a vertically disposed 100 shaft 5 which extends well into the interior of the casing, and has attached to its lower end, a movable contact bearing switch member in the form of a collar 6 of insulating 105 material. In order to prevent relative rotation of the collar 6 with respect to the shaft, the lower end of the latter is flattened, as best seen in Figs. IV and VIII, to fit a correspondingly shaped aperture in said 110 collar 6. Displacement of the collar is prevented by means of a washer 7 which may be secured to the shaft 5 in any suitable

manner. Recessed in the upper face of the collar 6 are segmental bridging contact plates 8, 8, which are preferably attached to said collar by screws 9, 9 accessible from beneath. The collar 6 has formed in it, radial notches or recesses 10 which underlie the terminal edges of the segmental contact plates 8, 8, and by way of which any metallic particles resulting from wear may 10 gravitate and escape under agitation of the fluid lubricant induced by rotation of the switch.

Surrounding the shaft 5 within the casing 1 is a fixed block of insulating material 11 which is preferably secured to the top of the casing by means of screws 12, 12 which engage within suitable offsets 13, 13 of the block clearly shown in perspective in Fig. VI. Said block 11 is pierced by a number 15 of apertures 15, 15 which extend longitudinally therethrough, and are disposed symmetrically about the central aperture 16 through which the shaft 5 extends. Slidable within the apertures 15 are a series of 20 plungers 17, 17 which are tubular in form and each constructed preferably of a sheet metal stamping bent to the desired shape, as shown in Fig. XI. The lower ends of 25 the plungers 17 are closed by shouldered plugs 18. Said plugs 18 are yieldingly held in engagement with the metallic contact segments 8, 8 of the collar 6 by means of the helical springs 19 which, for the most part, are accommodated within the hollows 30 of the tubular plungers. The upper ends of the springs 19 abut against a disk 20 of insulating material interposed between the block 11 and the top of the casing 1, said disk thus serving both as a closure for the 35 ends of the apertures 15, and as a means for preventing electrical contact between the ends of the springs 19 and the metal of the casing 1. The plungers 17, 17 are further provided with integral outstanding 40 projections 21 which terminate in eye 22 affording a means of attachment for the ends of electrical connectors 23, 23. The projections 21 of said plungers 17 pass 45 through slots 25 in the sides of the block 11. Said slots 25 communicate with the respective apertures 15 in a manner clearly shown in Fig. VI, and are open at one end of the block 11 so that the plungers 17 may be readily inserted in assembling the 50 switch. From Figs. IV and V, it will be noted that sufficient slack is allowed in the connectors 23 to permit the free action of the plungers 17, while the opposite ends of 55 said connectors have their source in terminal disks 26 embedded within a molding 27 of insulation, which hermetically seals the opening 28 through which the connectors emerge from the casing 1. The molding 27 is preferably joined with the casing 1 and the terminal disks 26 and portions of

connectors 23 embedded in the course of manufacture so that a hermetical seal is absolutely assured. The casing 1 is dovetailed as at 24 in Figs. IV and V, this construction assisting in the subsequent retainment of the insulation. As best seen in Figs. 70 IV and VII, the terminal plates 26 are exposed at one side and provided with screws 29 whereby the ends of the conductor leads of the circuits which are to be controlled, 75 may be attached to the switch,—suitable intervening webs 30 integrally formed with the insulation 27 serving to prevent short circuiting between the connections thus made. 80

When my invention is to be used as a wall switch in electric light circuits, etc., I prefer to use the actuating instrumentalities which are about to be described. To the protruding upper end of the shaft 5 is attached an 85 operating element 35 which, as shown in Fig. III, is in the form of a tri-arm comprising the extremities 36, 37 and 38. Fixed into the arm 36 at a suitable leverage distance from the axis 5 of the switch is a 90 pin 39, a portion of which extends below the said element 35 so as to be capable of cooperating with fixed stops 40, 41 on the top of the casing 1, said stops determining the limit to which the axis 5 may oscillate. 95 The extremities 37 and 38 carry, respectively, upstanding lugs or pins 42, 43 which are alternately engaged by hook notches 44, 44 of the arrow head extremity of a finger 45, in effecting oscillation of the element 35. 100

The finger 45 is further provided at either side at a point intermediate its length with cam lugs or projections 46, 46, which co-operate in turn with the pins 42 and 43 for a purpose which will be later described. Said finger is freely pivoted about a fulcrum stud 47, depending from a supporting slide 48 in the form of a sheet metal stamping which is guided in appropriate ways in bracket arms 49 rising from the casing 1. 105 The slide 48 is shiftable in opposition to a coiled spring 50 spanned between the pin 39 of the element 35 previously referred to, and the depending stud 47 of said slide under pressure applied to a push button 51 mounted upon an integral shank 52 of the slide. I prefer to mount the push button 51 in such manner that it may have capacity for a limited extent of free motion in opposition to a coiled spring 54 concealed within the hollow of said button as shown in Fig. IV. At its rear end, the spring 54 abuts against an integral upturned lug 55 of the shank 52 of the slide, and the button 51 is held in assembly with respect to the extension 52 by virtue of engagement of inwardly projecting tabs 56 (see Fig. X) with the inner ends of slots 57 formed in the element 52 (see Fig. IV). The compressive force of the spring 54 is consider- 110 115 120 125 130

ably less than the tension of spring 50 so that when the button 51 is pushed inwardly, the spring 54 will be the first to yield.

The switch proper is in turn protected 5 within a suitable metallic housing 60 which is closed at its front end by a removable plate 61 whereto the casing 1 of the switch is secured. Such attachment is effected preferably by stud bolts 62 and clamp nuts 63, 10 the exposed ends of the bolts at the interior of the casing 1 being covered preferably with solder in the course of manufacture, so as to afford a perfect seal in preventing leakage or escape of any of the liquor from the 15 casing. As shown in Figs. I, II and IV, the push button 51 is supported for guidance in an opening 64 in the plate 61, and protrudes through a clearance opening 65 in a flush plate 66, which serves to cover 20 the recess in the wall which is to accommodate the housing 60 in accordance with approved practice. The conductors 67 of the circuits which are to be controlled, enter the housing 60 through a pipe 68 secured within 25 an aperture 69 in a manner common to the connection of such electrical appliances.

The operation of the switch is as follows:

Let it be assumed that button 51 has been 30 pushed, and that the element 35 has been thrown by engagement of the pin 43 with the corresponding notch 44 of the finger 45 so that the pin 39 has been brought against the fixed stop 40. Upon release of the button, it will be apparent that the spring 50 35 immediately becomes effective in drawing the slide 48 forward until its tabs 53 come to a stop against the bracket arms 49 of the casing 1. In the course of this forward movement, the cam lug 46 of the finger 45 40 uppermost in Fig. III engages against the pin 43, thus causing the finger 45 to be swung counter-clockwise about its fulcrum 47 (Fig. III) so that the opposite notch 44 will be placed into a position to engage the pin 42 to swing the element 35 in a reverse 45 direction to that of its preceding movement upon the next succeeding depression of the push button 51. Thus in being reciprocated in the interval between the pins 42 and 50 43, the finger 45 will cause the alternate throwing of the plate 35 to one or the other of its positions, and cause corresponding movement of the switch in controlling the lights or other appliances in the circuit in 55 which said switch is interposed. It is to be noted that in either final position of the switch, the spring 50 will occupy an angular position to one side or the other of a plane common to the axis 5 of the rotation of the 60 switch and the anchorage pin 47. Furthermore, by reason of the allocation of the pins 39 and 47, respectively at opposite sides of the axis 5 of the switch, the spring 50, after 65 being shifted slightly beyond a dead centre line within the plane above referred to, will

become immediately effective in bringing about instantaneous movement of the element 35 in completing the oscillation begun or initiated by movement of the finger 45 in a manner already understood. This instantaneous or snap action promotes both the positive operation of the switch, and also quick separation of the switch contacts. At this time, the spring 54 within the button 51 not only allows the necessary independence of action of the spring 50 as noted, but assists in bringing about the snap action.

While I have shown and described in connection herewith, a movable switch member with contact segments 8 which serve to bridge but two of the contact plungers 17 in the immovable block 11, it is obvious that both the scope and number of bridging contacts and plungers may be varied in accordance with the functions which the switch 85 is to perform in practice.

Referring now to the embodiment shown in Fig. XIII, the switch proper, as here represented, is precisely the same in construction as in the embodiment first described, 90 but the instrumentalities by which its operation is effected differ in details which may be briefly pointed out as follows:

The housing indicated at 70 is of a somewhat more rugged construction than the 95 housing 60 of the first described form, although of substantially the same design, and has formed integrally with it, a boss 71 which is adapted to align with the axis or shaft 5 of the switch as shown. This boss 71 serves as a bearing for an auxiliary shaft 72 having an attached operating lever 73 at its outer end by which it may be coordinated with any apparatus whose movements are to be checked under signals controlled by the switch as mentioned in the preamble hereto. In order to obviate the necessity for absolute accuracy in mounting the switch, I prefer to construct the coupling between the operating shaft 72 and the shaft 5 of the 100 switch by providing the latter with a collar 75 having a tongue or projection which engages within an appropriate bifurcation within the lower end of the shaft 72. The 110 operation of the structure shown in Fig. XIII is thought to be obvious without necessitating special description.

The switch proper common to both embodiments of my invention herein described and illustrated, it will be particularly observed, is, in the course of its manufacture, completely assembled with all internal connections made according to use to which the switch is to be put. This obviates the necessity for disassembling or dismantling the switch when installations are to be made as required in switches heretofore intended for similar purposes.

From the foregoing, it will be readily seen that the simplicity of the switch of my 125

invention, both as to construction and operation, precludes the possibility of derangement in long continued usage, thus obviating the necessity of any attention whatever 5 as to the working mechanism or even with respect to the replenishment of the lubricating liquid. The initial charge of the liquid will last almost indefinitely, since its only possible avenue of escape (by capillarity 10 through the bearing 4) is rendered substantially liquid tight, by reason of the pressure exerted between the upper face of the bearing 4 and the contacting face of the hub of element 35 under action of the springs 19 15 which, as is already understood, exert at all times downward pressure on the shaft 15.

Having thus described my invention, I claim:

1. An electric switch comprising in combination, a closed, dust and moisture-proof, protective casing into which the leads of the conductors of the circuits to be controlled, are passed through a sealed opening; a rotatable shaft extending to the interior of the 20 casing; a movable, contact carrying switch member attached to the shaft within the casing; a fixed block of insulating material wholly contained within the casing adjacent said movable switch member; non-rotatable metallic plungers slidably disposed in retaining apertures of said block, said plungers being electrically connected with the conductor leads of the controlled circuits; means for yieldingly maintaining said 25 plungers in engagement with the contacts of the aforesaid movable switch member, and means capable of transportation to angular positions at opposite sides of the rotatable shaft for limiting movement of the switch.
2. An electric switch comprising in combination, a closed, dust and moisture-proof, protective casing into which the leads of the conductors of the circuits to be controlled, are passed through a sealed opening; a rotatable shaft entering the casing at 30 the top and extending well into the interior of the same; a movable, contact carrying switch member attached to the inner end of the shaft; an immovable block of insulating material mounted in axial relation about the shaft superjacent the aforesaid movable switch member and contained wholly within the casing; metallic plungers disposed for non-rotatable guidance in retaining apertures of the block, said plungers being 35 adapted for electrical connection with conductor leads of the controlled circuits; means for maintaining the plungers positively in yielding engagement with the contacts of the aforesaid movable switch member, and means capable of transportation to angular positions at opposite sides of the rotatable shaft axis for limiting movement of the switch.
3. An electric switch comprising in com-

bination, a metallic casing; a movable, contact carrying switch member disposed within said casing; an immovable block of insulating material fixed to the casing adjacent said movable switch member; tubular 70 metallic plungers disposed for non-rotatable guidance in retaining apertures of said block, said plungers being closed at one end and adapted for fixed electrical connection with conductor leads of the controlled circuits; 75 an insulating disk interposed between the casing and the block forming a closure for the apertures of the latter at one end; coiled springs for positively maintaining said plungers in engagement with the contacts 80 of the aforesaid movable switch member; said springs being accommodated, for the most part, within the hollows of the plungers and abutting at one end against the aforesaid insulating disk, and spring controlled means capable of transportation to angular positions at opposite sides of the rotative axis of the switch member and thereby limit movement of the switch.

4. An electric switch comprising in combination, a movable, contact carrying, switch member; an immovable block of insulating material located adjacent said movable switch member; metallic plungers guided in retaining apertures in said block, said plungers being bent, to tubular form, from sheet metal stampings and provided with integral clip extensions adapted to pass through appropriate slots in the side of the block to afford attachment for the ends of the conductor leads of the circuits which are to be controlled; and coiled springs for positively pressing said plungers into engagement with the contacts of the aforesaid movable switch member.

5. An electric switch comprising in combination, a closed, dust and moisture-proof, protective casing; a movable, contact bearing switch member disposed within said casing; an immovable block of insulating material located wholly within the casing adjacent said movable switch member; metallic plungers guided in retaining apertures of said block; means for maintaining said plungers in engagement with the contacts of the movable switch member; flexible electric conductor leads connected at one of their ends to the plungers under sufficient slack to permit free movement of the plungers, said leads extending through an opening of the protective casing and having their opposite ends coordinated with terminals embedded in a molding of insulation hermetically sealing said opening whereby the casing may be oil filled; and means whereby the conductors of the circuits to be controlled may be connected to the said terminals.

6. An electric switch comprising in combination, a rotary switch member; a control

100

105

110

115

120

125

130

shaft for said rotary switch member; and instrumentalities for oscillating the shaft to shift the switch member, including: an operating element attached to said shaft; stops for limiting the extent of oscillation of said element; a pair of lugs projecting from said element; a freely pivoted double hooked finger capable of being reciprocated within the interval between said lugs, and swung to position its hooks respectively for alternate engagement with the lugs in the course of successive actuations of the switch; cam projections on said finger in turn adapted for cooperation with the aforesaid lugs during the retractive movements of the finger in swinging the latter to alternate positions in readiness for engaging the lugs; a slide to which the finger is fulcrumed; and a spring for normally maintaining the slide and finger in retracted position.

7. An electric switch comprising in combination, a rotary switch member; a shaft for said rotary switch member; and instrumentalities for oscillating the shaft to shift the switch member including: an operating element attached to said shaft; stops for limiting the extent of oscillation of the element; a pair of lugs projecting from said element; a freely pivoted, double hooked finger adapted to be reciprocated within the interval between said lugs and swung to position its hooks respectively for alternate engagement with the lugs in the course of successive actuations of the switch; cam projections on said finger in turn adapted for cooperation with the aforesaid lugs during the retractive movements of the finger in swinging the latter to alternate positions in readiness for engaging the lugs; a slide to which the finger is fulcrumed; and a helical tension spring attached at one end to the slide, and at the other at a leverage to the aforesaid operating element, said spring being capable of transposition to angular positions at opposite sides of a plane common to its point of anchorage on the slide and the rotative axis of the switch, so that the element is normally yielding held against one or the other of its limiting stops, and the slide at the same time held normally in retracted position.

8. An electric switch comprising in combination, a rotary switch member; a control shaft for said switch rotary member; and instrumentalities for oscillating the shaft to shift the rotary switch member including: a tri-arm operating element attached to said shaft; fixed stops for limiting oscillation of said element; actuating means including a slidable member for initiating shifting of said tri-arm element into engagement with one or the other of said stops; an arrow-headed finger fulcrumed to said slidable member; and a helical tension spring attached at one end to said tri-arm element

at a leverage distance to one side of the axis of rotation of the switch, and at the other end to fulcrum of the finger so that when the tri-arm element is shifted in either direction to bring the centre of attachment of the spring to a position slightly beyond a dead centre line, said spring and arrow head finger become automatically effective in bringing about instantaneous completion of the movement of the switch element in the direction initiated by the action of the actuating means.

9. An electric switch comprising in combination, a rotary switch member; a control shaft for said switch rotary member; and instrumentalities for oscillating the shaft to shift the rotary switch member including: a tri-arm element attached to said shaft; fixed stops for limiting oscillation of said element; a slide capable of limited movement having an arrow-headed finger fulcrumed thereto for initiating shifting of said element into engagement with one or the other of said stops; a helical tension spring attached at one end to the tri-arm element at a leverage distance to one side of the axis of rotation of the switch, and at the other end to the fulcrum of the aforesaid finger so that when the tri-arm element is shifted in either direction to bring the centre of attachment of the spring to a position slightly beyond a dead centre line, said spring becomes automatically effective in bringing about instantaneous completion of the movement of the switch element in the direction initiated by the action of the actuating means; and a push button attached to the slide with capacity for independent motion in permitting the instantaneous movement of the switch element as aforesaid.

10. An electric switch comprising in combination, a rotary switch member; a control shaft for said switch rotary member; and instrumentalities for oscillating the shaft to shift the rotary switch member including: a tri-arm attached to said shaft; fixed stops for limiting oscillation of said tri-arm; a slide capable of limited movement having an arrow-headed finger fulcrumed thereto for initiating shifting of the tri-arm into engagement with one or the other of said stops; a helical tension spring attached at one end to the tri-arm at a leverage distance to one side of the axis of rotation of the switch, and at the other end to the fulcrum of the aforesaid finger, so that when the element is shifted in either direction to bring the centre of attachment of the spring to a position slightly beyond a dead centre line, said spring becomes automatically effective in bringing about instantaneous completion of the movement of the switch in the direction initiated by the action of the slide and an associate push button, said button being subject to an opposing spring adapted to

assist the said helical tension spring in effecting the instantaneous movement of the switch member as aforesaid.

11. An electric switch comprising a closed, 5 dust and moisture-proof, protective casing in which the mechanism of the switch is submerged in a suitable liquid lubricant, said switch mechanism including, a stationary contact supporting member of insulating material; and a movable contact supporting member also of insulating material, the metallic contacts of one of said elements being maintained in frictional engagement with spaced metallic bridging segments on

the other, and the latter provided, beneath 15 the terminal edges of the segments, with grooves by way of which metallic particles resulting from the wear of the contact elements are carried off under motion of the liquid lubricant induced during the operation of the switch.

In testimony whereof, I have hereunto signed my name at Philadelphia, Pennsylvania, this 7th day of April, 1921.

HERBERT I. WASHBURN.
